DESIGN FOR A CANDLE

Lester F. Wilson, San Gabriel, Calif.

Application March 24, 1939, Serial No. 83,807

Term of patent 14 years

To all whom it may concern:

Be it known that I, Lester F. Wilson, a citizen of the United States and residing at San Gabriel, in the county of Los Angeles and State of California, have invented a new, original, and ornamental Design for a Candle, of which the following is a specification, reference being had to the accompanying drawing, forming a part thereof.

In the accompanying drawing,

Fig. 1 is a side elevational view of a candle showing my new design;

Fig. 2 is a top plan view; and

Fig. 3 is an enlarged fragmentary sectional view thereof.

I claim:

The ornamental design for a candle, substantially as shown.

LESTER F. WILSON.
